HYDRAULIC MOTOR

Frederick A. Gruetjen, Alhambra, Calif., assignor
to A. O. Smith Corporation, Milwaukee, Wis.,
a corporation of New York

Application May 7, 1938, Serial No. 206,541

4 Claims. (Cl. 121—158)

This invention relates to reciprocating hydraulic motors.

An object of the invention is to provide an improved hydraulic motor of the reciprocating type.

Another object of the invention is to provide an improved reversing valve for controlling the distribution of power fluid to the cylinder of a reciprocating hydraulic motor.

Further objects of the invention will be clear from the accompanying description and the drawings in which:

Figure 1 is a view showing a longitudinal section through the cylinder of a hydraulic motor and its reversing valve embodying the invention, and also representing diagrammatically the various fluid conduits which connect the different ports in the cylinder of the motor and the body of the reversing valve;

Fig. 2 is a longitudinal section through the reversing valve similar to the view shown in Fig. 1 but with the pilot valve and main valve in opposite positions from those which they occupy in Fig. 1;

Fig. 3 is a longitudinal section on the line 3—3 of Fig. 5;

Fig. 4 is a longitudinal section on the line 4—4 of Fig. 14;

Fig. 5 is a top plan view of the reversing valve; Figs. 6 to 13 inclusive are transverse sections taken through the reversing valve on their respective section lines as indicated in Figs. 1, 3 and 4 of the drawings;

Fig. 14 is a bottom view of the reversing valve; and

Fig. 15 is a longitudinal section through a deep well pumping unit which employs a hydraulic motor to drive a reciprocating pump.

Referring to the drawings, and in particular to Figs. 1 and 2, the hydraulic motor comprises a piston 1 in a cylinder 2 which is connected by suitable ports and fluid conduits to reversing valve 3. The reversing valve has two piston valves sliding in their respective bores in valve body 4, these valves being pilot valve 5 and main valve 6. Fluid conduits shown schematically on Figs. 1 and 2 as 7, 8, 9 and 10 connect ports 11, 12, 13 and 14 in the cylinder of the hydraulic motor to ports 15, 16, 17 and 18 respectively in the body of the reversing valve. Ports 11 and 14 and their connected conduits 7 and 10 serve to admit power fluid to and to exhaust it from the two ends of the hydraulic cylinder 2. Ports 12 and 13 and their associated fluid conduits 8 and 9 are used to reverse the pilot valve and

consequently the main valve and the piston 1 of the hydraulic motor when the piston passes over one or the other of ports 12 and 13 during the course of its motion toward the respective end of cylinder 2. Power fluid for actuating the hydraulic motor is led to valve port 19 through fluid conduit 20. Conduits 21 and 22 conduct the power fluid exhausted from the motor away from valve ports 23 and 24. Conduits 25 and 26 connect ports 27 and 28 respectively to the lower and upper ends 29 and 30 of the cylindrical bore in which the main piston valve 6 slides. Fluid passageways 31, 32, 33, 34 and 35 cut in the valve body establish communication respectively between the following pairs of ports, 15 36 and 41, 37 and 23, 38 and 19, 39 and 24 and 40 and 42, of which the first port in each pair opens into the bore for the main valve and the second into the bore for the pilot valve.

When the pilot valve 5 has the position shown in Fig. 1, power fluid from conduit 20 is conducted through ports 19 and 27 and conduit 25 to the lower end 29 of the bore which houses the main valve 6. The upper end 30 of this bore is connected through conduit 26 and ports 28 and 24 to conduit 22 for receiving the fluid discharged from the hydraulic motor. Since both the main valve and the pilot valve are piston valves, they are balanced except against differences of pressure which may exist across their ends, and the greater pressure on the lower end of main valve 6 will therefore hold it securely in its extreme upper position. When the main valve is in this position, power fluid from conduit 20 is conducted through port 19, fluid passageway 33, ports 38 and 45, conduit 7 and port 11 to the lower end of the cylinder of the hydraulic motor. Port 14 at the upper end of the cylinder communicates through conduit 10, ports 16 and 39, passageway 34 and port 24 with conduit 22 for the reception of exhaust fluid from the hydraulic motor. Under these conditions the piston of the motor is driven upwardly as indicated by the arrow in Fig. 1.

The upper end 43 of the bore which houses the pilot valve communicates through slot 44 in the pilot valve, passageway 35, ports 40 and 47, fluid conduit 9 and port 13 with the upper end of the cylinder of the hydraulic motor. The pressure here is the exhaust pressure of the hydraulic motor and is substantially the pressure of the surrounding atmosphere. There is consequently, substantially no excess of pressure exerted on the upper end of the pilot valve 5 to shift it from the position shown in Fig. 1. A

spring detent 45 is provided at the upper end of the pilot valve, and a hydraulic lock 46 at the lower end to hold the pilot valve in position against the force of gravity, and also to insure that the pilot valve will not be thrown by small pressure fluctuations but only by the application of a pressure change exceeding some desired value which is determined by the construction of the spring detent and the hydraulic lock.

10 The valve operates to reverse the motion of the hydraulic motor according to the following sequence of events. Continued upward motion of the piston 1 as indicated in Fig. 1 first causes the piston to cover port 13 and to then uncover it, exposing it to the high pressure fluid which is in the lower end of the cylinder. This high pressure is transmitted through conduit 9, ports 17 and 40, fluid passageway 35 and slot 44 to the upper end of the pilot valve 5. Acting on 15 this end of the valve the high pressure forces it down against the opposition offered by the spring detent 45 and the hydraulic lock 46, the construction and operation of which will be explained in detail hereinafter. When the pilot valve 20 moves down, the lower end 29 of the main valve bore is connected through conduit 25 and ports 27 and 23 to the discharge pressure in conduit 21. The upper end 30 of the main valve bore is connected through conduit 26 and ports 25 28 and 19 to the power fluid entering the valve body through conduit 20. The main valve is therefore forced down in which position it reverses the flow of fluid through conduits 7 and 10 and consequently reverses the motion of the 30 piston in the hydraulic motor.

35 Restricted passageways or fluid chokes 47 (Fig. 4) are provided in fluid conduits 25 and 26 to throttle the flow of fluid through them and prevent a violent shift of the main valve 6 from one 40 end of its bore to the other. Suitable slots 48 are provided on the main valve 6 to insure a gradual reversal of the piston in the hydraulic motor, and to maintain sufficient pressure in the valve ports during reversal to insure that reversal of the valves will take place.

45 The hydraulic lock indicated generally at 46 comprises a cylindrical bore 49 in the pilot valve and a valve seat 50 in a bushing 51 which makes a tight fit in the cylindrical bore 49 and is held 50 in place by a rivet 52. A central opening 53 and vent holes 54 provide fluid passageways leading from the valve seat to the space below the pilot valve. A plunger 55 is pressed against valve seat 50 by a spring 56. Holes 57 and 58 bored in the 55 pilot valve provide communication between spaces 59 and 60 and ports 31 and 32. A slot 61 provides for a fluid passageway between spaces 59 and 62.

60 When the pilot valve has the position shown in Fig. 1, spaces 59, 60, and 62 are in communication with the discharge pressure from the motor. Since this pressure is substantially that of the surrounding atmosphere it has no resultant effect tending to shift the plunger 55 in one direction 65 or the other. The plunger is held tightly pressed against the valve seat 50 by spring 56. Space 63 below the pilot valve is filled with fluid as a result of the previous cycle of operations and as a consequence the pilot valve cannot move down 70 so long as plunger 55 remains on its seat 50 and prevents egress of fluid from space 63. Consequently slight pressure fluctuations or small forces are incapable of moving the pilot valve down. When, however, the piston in the hydraulic motor passes over port 9 and admits high

pressure fluid to the upper end of the pilot valve as previously described, the force is sufficient to drive the valve down, the fluid trapped in space 63 unseating plunger 55 against the pressure of spring 56 and escaping through slot 61, space 59 and hole 57 to passageway 31 and from there through ports 36 and 31, passageway 32 and port 23 to conduit 21 which is at exhaust pressure.

5 In the position of the valves shown in Fig. 2, spaces 59 and 60 are again both filled with fluid 10 at the discharge pressure of the hydraulic motor. Plunger 55 resting on valve seat 50 prevents flow of fluid to the region below the pilot valve where it would exert a force pushing the valve upward against the resistance offered by spring detent 15 45. In this position also the hydraulic lock operates to hold the pilot valve locked in position against small forces or fluid pressures which might otherwise move it to the other end of its bore. When, however, the motion of the piston 20 in the hydraulic motor carries it below the port 12, high pressure fluid is admitted to space 59, through a path readily traced on the drawings. This high pressure fluid acts on the annular area 25 between the valve seat 50 and the cylindrical bore in which plunger 55 slides, forces the plunger upward against the force exerted by spring 56, and passes through the opening 53 to the space 63 below the pilot valve where it exerts a force which shifts this upward against the resistance 30 offered by the spring detent 45. The main valve is then thrown up by the action of the pilot valve, and the piston of the hydraulic motor is reversed.

35 The course of the passageways and conduits provided in the valve body can be followed in 35 Figs. 3 to 14 inclusive in which the passageways and conduits have been identified by the same numerals used in Figs. 1 and 2.

40 Fig. 15 illustrates an application of the improved hydraulic motor and reversing valve of 40 this invention in connection with a deep well pumping unit for pumping crude oil or other fluid from a well. The pumping unit indicated generally by the numeral 64 comprises an electric motor 65; a pump 66 connected to the electric 45 motor for supplying power fluid to operate a hydraulic motor; a sump or reservoir 67 from which the pump 66 takes oil and into which the discharge from the hydraulic motor is returned; a hydraulic motor consisting of a reversing valve 50 3 and cylinder 2 with piston 1 and piston rod 68; and a crude oil pump 69 in which the piston rod 55 of the hydraulic motor acts as the plunger. In the embodiment illustrated the power oil which circulates through pump 66 and the hydraulic 55 motor does not come in contact with the crude oil pumped from the well and can be kept free from sand and grit or other substances which would injure the mechanism. A tubing string 70 is provided to conduct the crude oil to the surface, and an electric cable 71 to convey power to the electric motor.

60 In some cases it may be desirable to have pump 66 and its electric motor located at the surface of the ground from whence they supply power fluid 65 for the operation of the hydraulic motor through hydraulic tubing running from the surface of the ground to the submerged pumping unit. The power fluid discharged from the hydraulic motor can be conducted to the surface through another string of tubing in case it is desired to recirculate it and keep it free from admixture with the crude oil pumped from the well. In other cases it may be preferred to lead the discharge from the hydraulic motor directly to the tubing 75

used to carry the crude oil to the surface. This makes it possible to dispense with one string of tubing. When this is done fresh power fluid must be supplied continually to replace that which passes through the hydraulic motor and is then discharged into the crude oil line. This can frequently be a part of the crude oil pumped which is filtered and otherwise cleaned to remove substances which might have a deleterious effect upon the hydraulic motor.

10 The invention may have various embodiments within the scope of the following claims.

I claim:

1. In a valve structure for controlling the distribution of power fluid to the cylinder of a reciprocating hydraulic motor, the combination of a main valve for operating said motor, a pilot valve for controlling the main valve, means for admitting fluid under pressure to the pilot valve 15 to shift it from one position to another, and hydraulic means for locking the pilot valve in position until the pressure of the fluid tending to shift it exceeds a predetermined value.
2. A hydraulic motor comprising a cylinder, a 20 piston reciprocable therein, a fluid passageway connecting each end of the cylinder to the bore of a main valve for controlling the flow of fluid to and from the cylinder of the hydraulic motor, a main valve movable within the main valve bore, a bore for a pilot valve, a pilot valve movable therein, means actuated by the pilot valve 25 for shifting the main valve, a port to each side

of the center of the main cylinder traversed by the piston in its travel, fluid passageways connecting said ports to the bore of the pilot valve, and resilient means preventing flow of fluid in such passageways unless the pressure which tends to cause said flow exceeds a predetermined value.

3. In a hydraulic motor comprising a cylinder, a piston, and a main valve actuated by a pilot valve, the combination of a pilot valve bore, a 10 pilot valve reciprocable therein, ports within the pilot valve bore to control the flow of fluid through the pilot valve to an end of the pilot valve bore where it would exert a pressure upon the pilot valve tending to shift it from this end 15 of the bore, and resilient means carried by the pilot valve for preventing such flow of fluid through it when the pressure tending to cause said flow is less than a predetermined value.

4. In a valve structure for controlling the distribution of power fluid to the cylinder of a reciprocating hydraulic motor, the combination of a main valve for operating said motor, a pilot valve for controlling the main valve, means for admitting fluid under pressure to the pilot valve 20 to shift it from one position to another, and spring-pressed hydraulically operated means for locking the pilot valve in position, said last named means being responsive to the pressure of the fluid tending to shift the pilot valve for releasing 25 the lock.

FREDERICK A. GRUETJEN.
